Patented Feb. 13, 1917.

2 SHEETS—SHEET 2.

By his Attorney, Inventor
Frank C. Fischer

UNITED STATES PATENT OFFICE.

FRANZ A. FULLER, OF NEWARK, NEW JERSEY, ASSIGNOR TO THE J. E. MERGOTT COMPANY, OF NEWARK, NEW JERSEY, A CORPORATION OF NEW JERSEY.

PAD-HOLDER.

1,215,643.

Specification of Letters Patent. Patented Feb. 13, 1917.

Application filed October 14, 1915. Serial No. 55,789.

To all whom it may concern:

Be it known that I, FRANZ A. FULLER, a citizen of the United States, residing in the city of Newark, in the county of Essex and 5 State of New Jersey, have invented certain new and useful Improvements in Pad-Holders, of which the following is a full, clear, and exact description, such as will enable others skilled in the art to which it pertains 10 to make, construct, and use the same, reference being had to the accompanying drawings, and to numerals of reference marked thereon, forming a part of this specification.

15 My invention relates to a combination desk calendar and pad, and its object is to provide a simple and novel device of this character, which may be utilized for a number of purposes, such as to furnish a calendar, paper weight, paper clip, or other convenient and useful device.

The present invention consists primarily in a novel device of the character described, to be hereinafter set forth, and furthermore, 25 this invention consists in the various novel arrangements and combination of parts, all of which will be described in detail in the following specification, and then finally embodied in the clauses of the claims.

30 The invention is clearly illustrated in the accompanying drawings, in which—

Figure 1 represents a plan view of my improved device, with the stamp compartment in an open position.

35 Fig. 2 represents a central section taken on line 2—2 of Fig. 1, and looking in the direction indicated by the arrows, the calendar compartment, shown in dotted lines, swung over the pad, and the hinged lid or 40 cover of the calendar compartment, shown in dotted lines, in open position.

Fig. 3 represents a sectional view of the calendar compartment taken on line 3—3 of Fig. 6, and looking in the direction indicated by the arrows.

45 Fig. 4 represents a similar view taken on line 4—4 of Fig. 6, and looking in the direction indicated by the arrows.

Fig. 5 represents a sectional view taken on 50 line 5—5 of Fig. 4, and looking in the direction indicated by the arrows; and

Fig. 6 represents a fragmentary enlarged view of the device.

Similar numerals of reference refer to

like parts throughout the specification and 55 drawings.

In the drawings, 1 designates the back plate of the device, preferably made of metal or any other suitable material, provided near its upper edge with an aperture 2, by means 60 of which the device can be hung upon a nail or the like, if desired. Arranged near the longitudinal edges of the back plate, and near the top edge thereof, are two aligned slots 3, to receive the upturned apertured 65 ears 4, extending upwardly from the ends of the curved body portion of the bracket 5. Each ear 4 adjacent to the curved body portion of the bracket 5, is provided with a recess 6 at one side, and with an enlarged portion 7 on the curved side, whereby said bracket 5 is secured to the back plate 1 without any additional fastening means, as clearly indicated in Fig. 5 of the drawings.

8 represents a spring actuated jaw, which 75 is provided with a pair of apertured ears 9, which overlap and are mounted upon and pivotally secured to the apertured ears 4 of the brackets 5, said jaw 8 being normally held closed under tension by the spring 10 80 coiled around a tube 11, which is interposed between the ears 4 and held in position by means of pivot pins 12 which enter the interior of the tube 11, the heads of which bear against the apertured ears 9. 85

The front portion 13 of the jaw 8, which extends beyond the apertured ears 9, terminates preferably in a curved portion, which engages with the pad of paper or with the back plate 1 when the pad is removed. 90

A calendar compartment, comprising a back plate 14 and a hinged lid or cover 15, the lower half of which is preferably provided with an embossed portion to be utilized for advertising purposes, and the upper half of which is provided with a cut-out portion to expose the calendar, picture or the like, is secured to the back plate 14, near the rear edge thereof, in the following manner:

The lid or cover 15 is provided with a downwardly extending flange 16, that portion of the flange at the top edge of the lid or cover being curled inwardly to form a tubular bearing 17, for the reception of the 105 wire rod or pintle 18. The ends of the pintle 18 are bent downwardly and passed through suitable apertures formed in the lugs 19, on

the back plate 14, and are then clenched upon the underside of said back plate. A finger piece 31 pierced from the lid or cover 15 is located near the lower edge of the lid, thereby providing means for releasing the lid from locking engagement with the lug 20, said lug being provided with a pressed-out portion 21, which has locking engagement with the flange of the lid or cover adjacent to the finger piece 31.

10 Located within the compartment are a series of calendar cards 22, or there may be a picture or the like. The calendar cards 22 are the day cards, and the cards 32 represent the month cards. The day cards as clearly indicated in Fig. 1 of the drawings, are shorter than the month cards, in order to expose the name of the month. 33 represents a thin sheet of transparent material, such as celluloid or the like. The marginal flanges 23 extending along the edges of the back plate 14, provide means for positioning and guiding the flanged cover or lid 15 on the back plate 14. The back plate 14 at its lower edge, is provided with a tubular bearing 24, formed by curling the metal of said back plate rearwardly for the reception of the wire rod or pintle 25, by means of which the compartment is pivotally secured to the 15 jaw 8 in the following manner: The jaw 8 is provided with a rearwardly depressed portion 26, at the end of which apertures are formed, and in this rearwardly depressed portion the tubular bearing 24 is located and the ends of the wire rod or pintle 25 pass through the apertures 27, and engage with outwardly pressed portions 28, which are in alignment with the rearwardly pressed portions 26, and project outwardly 20 from the bracket 8, and which form bearings for the pintle, see Fig. 1 of the drawings. A lug 29 is forced rearwardly from the back plate 14, said lug being provided with a pressed-out portion 30, designed to have locking engagement with the upper edge of the jaw 8, when the compartment is to be held in the position shown in Figs. 2 and 6 of the drawings.

An aperture 34 is formed in the jaw 8, 25 designed to receive the finger piece 31 of the lid or cover 15, when the calendar compartment rests upon the pad, as shown in dotted lines in Fig. 2 of the drawings.

A compartment 35 for stamps or the like, 30 provided with a suitable knob or finger piece 36, preferably made from a single piece of suitable material, is slidably secured to the back plate 14 of the calendar compartment, the marginal edges of said compartment 35 having sliding engagement with suitable guides 38 secured to the rear of the back plate 14 in any convenient or desired manner. The back plate 14 of the calendar compartment, is provided with a series of integral lugs 37, which are preferably struck

up from and extend outwardly from said plate, designed to provide means for properly limiting the outward movement of the compartment 35.

All of the parts of this device are preferably made from sheet metal, and are of such shape as to lend themselves readily to manufacture by the use of suitable punches and dies.

70 Experience has demonstrated that the organization above described is a highly efficient one, and while the device described is the preferred embodiment of my present invention, I do not care to restrict myself to the exact details of construction, combination and arrangement herein set forth, it being obvious that minor variations thereof, 75 not involving the exercise of invention, may be made by any skilled mechanic, and such departures from what is herein described and claimed, not involving invention, I consider as within the scope and terms of my claims.

Having described my invention, what I 80 desire to claim and have protected by Letters Patent is:—

1. A device of the character described, 85 comprising a back plate, a spring-actuated jaw pivotally connected to one end of said back plate, and a compartment adapted to hold a card or the like carried by said jaw.

2. A device of the character described, 90 comprising a back plate, a jaw pivotally connected to one end of the back plate and a compartment, one end of which is pivotally connected to said jaw.

3. A device of the character described, 95 comprising a back plate, a spring-actuated jaw pivotally connected to one end of said back plate, a compartment adapted to hold a card or the like carried by said jaw and a second compartment slidably secured to the back of the first-named compartment.

4. A device of the character described, 100 comprising a back plate, provided with apertured ears, a jaw provided with apertured ears pivotally connected to the said ears of the back plate and a compartment, one end of which is pivotally connected to said jaw.

5. A device of the character described, 105 comprising a back plate, a jaw pivotally connected to one end of said back plate, and a compartment, one end of which is pivotally connected to said jaw and a second compartment secured to the back of the first-named compartment.

6. A device of the character described, 110 comprising a back plate, a jaw pivotally connected to the back plate, a spring coiled around the pivot to normally hold said jaw closed under tension, a compartment pivotally connected to said jaw adapted to hold a card or the like, said compartment being 115 provided with locking means adapted to 120 125 130

have holding engagement with the rear edge of the jaw to hold said compartment in a raised position.

7. A device of the character described, comprising a back plate, a bracket provided with apertured ears removably secured to said back plate, a jaw provided with apertured ears pivotally connected to said bracket, a spring coiled around the pivot 10 to normally hold said jaw closed under tension, a compartment pivotally connected to

said jaw adapted to hold a card or the like, and a second compartment adapted to hold stamps or the like secured to the rear of the first-named compartment.

This specification signed and witnessed this 12th day of October, 1915.

FRANZ A. FULLER.
